ORTHO - ETHOXY - N - N - DIETHYLBENZAMIDE INSECT REPELLENT COMPOSITIONS AND PROCESS OF APPLYING SAME

Edward T. McCabe, Hyattsville, Md.; dedicated to the
free use of the People in the territory of the United
States

No Drawing. Application February 26, 1953,
Serial No. 339,188

8 Claims. (Cl. 167—30)

(Granted under Title 35, U. S. Code (1952), sec. 266)

A non-exclusive, irrevocable, royalty-free license in the
invention herein described, for all governmental pur-
poses, throughout the world, with the power to grant sub-
licenses for such purposes, is hereby granted to the Gov-
ernment of the United States of America.

The invention herein described is hereby dedicated to
the free use of the people in the territory of the United
States.

This invention relates to a new insect repellent and to a
method for its preparation.

It has been found that ortho-ethoxy-N,N-diethylben-
amide, a compound having the formula

when applied to either the human skin or articles of cloth-
ing affords effective protection against insect bites by
repelling the insects. This protection is particularly ef-
fective against *Aedes aegypti*. In using the new repellent
compound, it may be applied either alone or in an inert
carrier.

A number of tests to measure the repellency of this
compound against *Aedes aegypti* was conducted by spreading
the material on the arms of test personnel, who then
thrust their arms into cages containing the mosquito. The
arms were exposed at 30-minute intervals for 3 minutes
each or until the first insect bite. It was found that the
application of ortho-ethoxy-N,N-diethylbenzamide to the
skin affords protection against *Aedes aegypti* for an aver-
age of 308 minutes.

Tests to measure the repellency of this compound as an
impregnant for fabric against *Aedes aegypti* were con-
ducted by uniformly impregnating mercerized cotton hose
with the compound at a rate equivalent to 3.3 grams per
sq. ft., drawing the hose over the arms of test personnel,
who then thrust their covered arms into cages containing
Aedes aegypti for 1 to 2 minutes. If no bites or less
than 5 bites were received the tests were repeated on each
successive day until five or more bites during one expo-
sure were received. It was found that fabric impregnated
with ortho-ethoxy-N,N-diethylbenzamide remained re-
pellent against the mosquito for at least 37 successive days.

For ease of application to the skin the ortho-ethoxy-
N,N-diethylbenzamide is incorporated in a suitable inert
liquid or solid carrier. The following examples are merely
illustrative of the invention and are not intended as lim-
itations of its scope.

20 parts by weight of ortho-ethoxy-N,N-diethylben-
amide are mixed with 80 parts by weight of carrier to
produce the following compositions:

2

- (1) 20 parts amide with 80 parts of isopropanol.
- (2) 20 parts amide with 80 parts of mineral oil.
- (3) 20 parts amide with 80 parts of petrolatum.
- (4) 20 parts amide with 80 parts of a white emulsion
of fatty acid esters mixed with water. This composition
is obtained by mixing 20 parts of the amide with 20 parts
of the fatty acid esters, pouring the mixture into sufficient
water to make a total of 100 parts, and then emulsifying
the mixture.
- (5) 20 parts of amide with 80 parts of a standard zinc
oxide ointment.

The compound, ortho-ethoxy-N,N-diethylbenzamide is
a new compound and was prepared as follows:

18.4 grams (0.1 mole) of ortho-ethoxybenzoyl chloride
dissolved in 50 milliliters of dry ether is slowly added to
a cooled solution of 14.6 grams (0.2 mole) of diethyl-
amine dissolved in 100 milliliters of dry ether. After the
reaction product has been stirred for 1 hour at room tem-
perature, enough cold water is added to dissolve the pre-
cipitated diethylamine hydrochloride. The reaction mix-
ture separated into two layers, namely, an ether and an
aqueous layer. The ether layer is separated and washed
successively with 100 milliliter portions of 5% hydro-
chloric acid solution, water, 5% sodium hydroxide solution,
water and finally with a saturated solution of sodium
chloride. After the ether extract has been filtered
through a cotton plug, the ether is removed at the water
pump and the residue is purified by vacuum distillation.
A water-white distillate is obtained, boiling point 121° C.
at 0.1 mm., $n_D^{25} = 1.5160$.

One nonobvious advantage of this repellent is that it
does not harm or deleteriously affect plastic materials
such as watch crystals, eyeglass frames or fountain pens
usually found on or about the person to whom the repel-
lent will be applied.

- Having thus described my invention, I claim:
1. An insect repellent fabric comprising fabric im-
pregnated with ortho-ethoxy-N,N-diethylbenzamide.
  2. An insect repellent composition comprising ortho-
ethoxy-N,N-diethylbenzamide in an inert insecticidal ad-
juvant as a carrier therefor.
  3. The composition of claim 2 wherein the carrier is
isopropanol.
  4. The composition of claim 2 wherein the carrier is
mineral oil.
  5. The composition of claim 2 wherein the carrier is
petrolatum.
  6. The composition of claim 2 wherein the carrier is
an emulsion of fatty acid esters in water.
  7. The composition of claim 2 wherein the carrier is
a zinc oxide ointment.
  8. A process of repelling insects comprising applying
ortho-ethoxy-N,N-diethylbenzamide to the region from
which the insects are to be repelled.
